United States Patent Office.

BENJAMIN P. LAMASON AND SAMUEL W. MURRAY, OF MILTON, PENNSYLVANIA.

Letters Patent No. 69,226, dated September 24, 1867.

IMPROVED BRAKE-BLOCK AND SHOE FOR RAILROAD CARS.

The Schedule referred to in these Letters Patent and making part of the same.

TO ALL WHOM IT MAY CONCERN:

Be it known that we, BENJAMIN P. LAMASON and SAMUEL W. MURRAY, of Milton, in the county of Northumberland, and State of Pennsylvania, have invented a new and useful improvement on Brake-Blocks and Shoes for Railroad Cars; and we do hereby declare that the following is a full, clear, and exact description of the construction and operation of the same, reference being had to the annexed drawings, and the letters of reference marked thereon, making a part of this specification, in which—

Figure 1, in plans A and C, are side elevations, showing the block and shoe adjusted ready for use.

Figure 2 are longitudinal sections, showing the mode of adjusting and securing shoe to block.

Figure 3 are front views of brake-blocks, showing their construction.

Figure 4 are back views of brake-shoe, showing T-lug and hook.

Figure 5, sectional view through a a.

Figure 6, sectional views through b b and d d.

Figure 7, sectional view through c c.

To enable others skilled in the art to make and use our invention, we will proceed to describe its construction and operation.

Description of Plan A.

We construct our brake-block and shoe of cast iron, of the desired form and size. The shoe E, fig. 4, is provided with a T-shaped lug, seen at A. The body of this lug A is round in form, and is placed near the top end of shoe. The flanges o o, seen in figs. 4 and 5, extend across the shoe, and are less in width than the diameter of the body of lug. The lower end of shoe E is provided with a grooved hook, seen in figs. 4 and 7. e hook, J groove. Our brake-block we construct with an opening near the top, seen at B, fig. 3. This opening is made to conform in size and shape to the lug A. The lower end of block D is so constructed as to pass back of the hook e. This end of block is also provided with a hole, seen at I, fig. 6, which conforms in size with the groove J in hook e.

The mode of operating the block and shoe is as follows, being constructed as above described: The block D is secured to the wooden beam F by means of the bolt k. The shoe E is held by the hands at right angles with the block D; being thus in position, the lug A is passed through the opening B in block D, and is forced back sufficient to allow the flanges o o on lug A to pass back of the shoulders h h on block D, as seen in fig. 5. When thus in place the shoe E is turned around into position parallel with the block D. This movement of the shoe brings the flanges o o in the position shown in fig. 5. This device forms a secure fastening at this point. The body of the lug A being round fits neatly in the round portion of the opening B, thus preventing any upward or downward movement. The shoe E thus adjusted, the lower end passing within the hook e, the hole I and groove J are also brought in position; the pin f is then passed through them, securing them at this point. On block and shoe being constructed and secured as herein stated, it will be very readily seen that it forms a simple and secure arrangement, and fully meets the object in view. The brake-block and shoe adjusted ready for use is represented in fig. 1. Fig. 2 represents a longitudinal section, showing the manner of securing, &c.

Plan C is a modification of the above. The form of the lug is substantially the same, but in it the shoe is not turned but drops down directly in place and is held by the jointed pin K. The fastening at the bottom is effected by inserting the projection e in the hole i, arranged for the purpose in the lower part of the brake-block.

The advantages we claim for our improved brake-block and shoe, when constructed as herein described, are its simplicity, and the ease and facility with which it is adjusted. When desired, the shoe can be removed from the block and replaced in a very short time.

What we claim as new, and desire to secure by Letters Patent, is—

1. The brake-shoe E, provided with circular lug A, with flanges o o, in combination with the shoe D, with its opening B, of construction corresponding to the lug, the shoe and block being arranged to turn, and to be held in place by pin f, as and for the purpose set forth.

2. The lug A' with its flanges o' o', in combination with the block D' and pin K, all constructed and operating as described and for the purpose set forth.

BENJ. P. LAMASON,
S. W. MURRAY.
